TYPEWRITER COMPANY, OF NEW YORK, N. Y., A CORPORATION OF DELAWARE.

TYPE-WRITING MACHINE.

1,007,746.

Specification of Letters Patent.

Patented Nov. 7, 1911.

Application filed April 27, 1909. Serial No. 492,526.

To all whom it may concern:

Be it known that I, BURNHAM C. STICKNEY, a citizen of the United States, residing in Elizabeth, in the county of Union and State of New Jersey, have invented certain new and useful Improvements in Type-Writing Machines, of which the following is a specification.

This invention relates to the line-feeding mechanism of typewriting machines; and one of its main objects is to provide simple, compact and inexpensive means for effecting adjustments of the platen otherwise than by the usual line-spacing lever; and particularly to provide simple and convenient means for turning the platen through relatively great distances backwardly and forwardly for condensed billing.

Another object is to provide suitable means for advancing the platen automatically to produce a blank line between entries on the carbon sheet.

Another object is to enable the mechanism to be used also for effecting fine adjustments of the platen.

In the accompanying drawings, Figure 1 is a plan of a typewriter carriage provided with one form of my improvements. Fig. 2 is a sectional detail of a lever provided with a sliding line-spacing pawl. Fig. 3 is a sectional end elevation of the line-spacing mechanism. Fig. 4 is a sectional front elevation of the devices seen at Fig. 1, omitting the casing in which the line-spacing mechanism is inclosed. Fig. 5 is an end elevation of the devices seen at Fig. 1, the platen axle being shown in section. Fig. 6 is a plan of a cam collar, showing part of the means for automatically advancing the platen while the machine is used for condensed billing. Fig. 7 is a plan of a rotatable head, which is to receive the crank seen at Figs. 1 and 5, and which also is intended to carry certain of the line-spacing devices. Fig. 8 is a plan of a sliding collar by which movement is transmitted to the line-spacing devices.

The drawings show a platen-frame comprising front and rear bars 1 and 2, and end bars 3 and 4. Through said end bars extends an axle 5; provided at each end with a finger-wheel, as at 6 and 7, for rotating a cylindrical platen 8 secured to said axle; collars 9 and 10 being provided for prevent-

ing endwise displacement of the axle and platen. Upon the axle within the platen-frame and at the left-hand end of the platen-frame is secured a line-space ratchet wheel 11, by means of a hub 12 and screw 13, the ratchet-teeth 14 being upon the outer face of the wheel. Line-spacing mechanism 15 adapted to said ratchet wheel is mounted upon a revoluble head, comprising a hollow shaft 15 having at its inner end near said ratchet-wheel opposite bent arms 16 and 17; said shaft at its outer portion being journaled in the side-bar 3 of the platen-frame, as at 18, and being hollow to afford a bearing for the platen-axle 5 which extends entirely through the same. Said line-spacing mechanism comprises a lever 19, hinged at 20 and 21 upon reflexly bent cross-arms 22 and 23 secured upon said revoluble head; the pintle of the hinge being designated as 24, and said lever having the form of a bail which embraces said bearing arms. Upon one end of the lever is formed a cylindrical housing 25 for a sliding pawl 26, provided within the housing with a compression spring 27 coiled about a stem 28 formed upon the pawl, said stem being provided with a cap 29 to limit the projection of the pawl from the housing. As seen at Fig. 1, the pawl stands normally clear of the line-space ratchet wheel, so that the platen may be freely rotated by either finger-wheel 6 or 7; while by movement about the axis 24, the pawl may be swung into engagement with the ratchet-wheel to rotate the same. Upon the end of an arm 30, also formed upon said revoluble head, is pivoted at 31 a detent, in the form of a lever, one arm 32 whereof carries a roller 33 which engages the notches in the ratchet-wheel, while the other arm 34 is connected by a draw-spring 35 to an arm 36, the latter forming an extension of one of the bail-arms of the lever 19. The spring thus serves the two-fold purpose of applying pressure to the detent and returning said lever to normal position after actuation.

It will now be perceived that the platen may be rotated by either of its finger-wheels, or given a line-space movement by the lever and pawl; and that it is always held against accidental rotation by the detent; and also that by rotating the revoluble head, together with the lever, pawl and de-

tent thereon, the latter carries with it both the ratchet-wheel and platen; whereby exceptional rotative adjustments of the platen may be effected, together with the paper thereon, thereby facilitating writing upon ruled lines, making corrections, etc.; while at all positions to which the head may be adjusted, the lever and pawl may be operated to effect the line-spacing movement 10 of the platen. For rotating said head, a crank 37 is provided upon the end thereof that projects from the platen-frame; and for holding the head against accidental revolution a brake is employed, comprising a 15 spring 38 housed in the end 3 of the platen frame and bearing against a plug 38^a loose in the same bore 38^b which confines the spring, and pressed by the latter against the journal of the rotated head 15; said journal 20 being enlarged in diameter to increase the friction, and a shoulder 39 being formed at the inner end of said journal to prevent displacement of said head toward the left. The tension of the spring 38 may be regulated by 25 a screw 38^c; said spring being sufficiently powerful to hold the revoluble head steady at the line-spacing operation, and being considerably superior in efficiency to the detent 32, so that the resistance of the latter may 30 be overcome without stirring the revoluble head.

A line-spacing lever 40, consisting of a curved finger-piece 41 and a main forked portion 42, which bestrides the front carriage-bar 1 and the platen axle, is mounted upon a vertical pivot 43 in rear of the platen axle, and is adapted to swing from normal position toward the right at Fig. 1, or in the direction of the return movement of the 40 carriage. The connection between said carriage lever and the pawl-carrying lever 19 which is mounted upon the revoluble head, comprises a sleeve 44, splined by means of pin 45 and slot 46 to the tubular member 15 of said revoluble head; said sleeve having at its outer end a shoulder 47 engaged by opposite pins 48, 49 fixed upon the line-spacing lever 40, and having at its inner end a pin 50 engaging a radial slot 51 formed in 50 a spur 52 formed upon the lever 19. By means of the spline, the sleeve 44 is caused to rotate with the revoluble head, but may move therealong, the latter movement being effected by the pins 48, 49 and annular 55 shoulder 47, so that the carriage lever 40 may effect a movement of the lever 19 at any point to which the revoluble head may be adjusted, and thereby effect a line-spacing or step-by-step rotation of the platen. 60 It will be seen that the pawl 23, which is normally out of engagement with the line-space wheel, to permit the platen to be rotated by hand freely in either direction, is swung into engagement with the ratchet- 65 wheel by means of the initial movement of

the carriage lever 40, and then drives the wheel and platen around the desired distance.

The line-spacing stroke of the carriage lever 40 may be regulated by means of an adjustable stop 53; having the form of a sleeve mounted upon the front carriage-bar 1 in position to be engaged by the upper fork of the lever, to arrest the same at the completion of the line-spacing stroke. The sleeve may be adjusted along the bar, and is provided on its upper side with a projection 54, adapted to be inserted in any one of a series of three holes 55 formed in a yielding keeper 56, the latter being secured to the carriage bar by a screw 57, and provided at its free overlying end with a finger-piece 58, whereby it may be raised clear of the pin 54. The lever 40 will throw one, two or three line-spaces, according to the adjustment of the sleeve-stop 53.

It will be perceived that the spring 35, which controls the ratchet-wheel detent, serves also by reason of its connection to an arm of the lever 19, to return the latter to normal position after actuation, together with the sleeve 44 and lever 41. It will be further understood that during the line-spacing operation the swing of the arm 36 is sufficient to increase the tension of the 95 spring 35 materially, whereby the detent roller 33 is pressed with great force against the ratchet-wheel at the completion of the line-spacing stroke; and consequently the increased effectiveness of said detent at this moment may be relied upon to prevent overthrow of the platen. That is to say, the pressure of the detent may be normally so slight as to permit free rotation of the platen by the hand-wheels 6 and 7, but may by the described means be rendered so powerful at the completion of the line-spacing movement of the platen as to prevent its overthrow.

As illustrated at Figs. 1 and 3, a cylindrical casing or drum 59 incases the ratchet-wheel, the revoluble head and the parts thereon to protect the parts from injury and to contribute to the neat and compact appearance of the machine. The crank 37, which has a handle 60, is formed upon its opposite sides with a series of notches or teeth 61 which form a double rack. A stop 62 is formed to bestride the crank and slip into the notches and may be adjustable 110 along the crank. Upon the platen frame is secured by screws 63 a plate 64 having thereon a series of facets 65 to be engaged by the stop 62 to limit the initial stroke of the crank and platen. These stops 65 form a volute series, being located successively at increasing distances from the platen axle 5 to correspond with the location of the notches 61 on the crank 37. When it is desired to have the stop 62 engage with the 125

70

105

110

115

120

125

130

first stop 65, the stop 62 is placed in the first pair of notches, as shown at Fig. 5. The stops are placed at angular intervals agreeing with those of the teeth of the line-space wheel 11; and when it is desired to turn the platen backwardly from the normal Fig. 5 position to an extent greater by one or more line spaces, the stop 62 is adjusted to the second, third, fourth or other notch as the 10 case may be. By adjusting the stop to the top notch, a movement of the crank and platen is permitted about four fifths of a revolution from normal position. The invention is not limited to this construction of 15 stops or adjustment. The handle 60 is grasped, and the platen swung backward thereby to a point determined by the previous adjustment of the stop 62, and then the written bill is removed from the machine, 20 and a fresh bill blank substituted; the record and carbon sheets remaining in the machine, as usual in condensed billing. Then the handle 60 is grasped and the platen turned forwardly thereby, until arrested by 25 a stop 66 projecting from the plate 64 in the path of a lug 67 formed on the hub of the crank 37; said stop 66 determining the initial or normal position of the crank.

It will be seen that the crank remains 30 stationary during the line by line movement of the platen effected by the lever 42 or the platen knobs 6, 7. At any time the handle 60 may be grasped to rotate the platen through the detent 33.

35 The automatic advance of the platen to produce a blank space between bill entries on the record sheet is effected by means of a face or helical cam 68 formed upon a collar 69, which is secured by screws 70 to the 40 head 15, said collar 69 fitting the hub of the crank 37 and the side of the platen frame end 3, to prevent displacement of said head toward the right. Said cam 68 engages a 45 horizontal thrust pin 70, which extends parallel with the axis 5, and is mounted for a sliding movement in a perforation 71 formed in the platen frame end. At its outer end, it bears against the shoulder 47 upon the sliding collar 44. When therefore 50 the crank is swung over forwardly to give the initial rotation to the platen, the cam 68 forces the pin 70 to the left at Fig. 1 together with the collar 44, and the line-spacing lever 19 is vibrated into engagement 55 with the line-space wheel, and the latter is accordingly advanced one or more notches according to the form and extent of the cam 68, thus producing a blank space between entries on the carbon sheet. During the 60 return stroke of the crank 37, the collar 44 is returned to normal position by the spring 35 together with the pin 70.

When desired, the screw 70 may be unscrewed to release the collar 69, so that the 65 platen may be turned without affecting the

automatic advance feed of the platen and paper; and the crank 37 may be then used freely for effecting fine adjustments in the position of the platen and the paper, for writing upon ruled lines, and other purposes; and when desired the stop 66 may be detached. The lever 42 may always be used to line-space the platen, regardless of the adjustment of the crank or other driver 37.

Variations may be resorted to within the 70 scope of the invention, and portions of the improvements may be used without others.

Having thus described my invention, I claim:

1. In a typewriting machine, the combination with a revoluble platen and a platen frame, of a line-space wheel connected to the platen, a head mounted to turn concentrically with the platen, a brake to resist turning of said head, a line-spacing mechanism including both a driving-pawl mounted on said head and a lever mounted upon the platen frame to operate said pawl, a line-space wheel check or detent mounted on said head, a crank or driver connected to said head to turn the same against the opposition of said brake, and stops to limit the strokes of said head and platen. 80

2. In a typewriting machine, the combination with a revoluble platen and a platen frame, of a line-space wheel connected to the platen, a head mounted to turn concentrically with the platen, a brake to resist turning of said head, a line-spacing mechanism including both a driving-pawl mounted on said head and a lever mounted upon the platen frame to operate said pawl, a line-space wheel check or detent mounted on said head, a crank or driver connected to said head to turn the same against the opposition of said brake, and stops to limit the strokes of said head and platen, one of 90 said stops adjustable to vary the stroke of said head and platen. 100

3. In a typewriting machine, the combination with a revoluble platen and a platen frame, of a head mounted on the platen frame to turn concentrically with the platen, a brake to resist turning of said head, a line-space wheel, a spring check or 110 detent, one of said wheel and detent elements mounted on the platen and the other on said head, a finger-piece on said head, and an adjustable stop for said head. 115

4. In a typewriting machine, the combination with a revoluble platen and a platen frame, of a head mounted on the platen frame to turn concentrically with the platen, a brake to resist turning of said head, a line-space wheel, a spring check or 125 detent, one of said wheel and detent elements mounted on the platen and the other on said head, a finger piece on said head, a line-spacing device including a pawl and lever, both mounted on one of said head and 130

- platen elements, and an adjustable stop for said head.
5. In a typewriting machine, the combination with a revoluble platen and a platen frame, of a head mounted on the platen frame to turn concentrically with the platen, a brake to resist turning of said head, a line-space wheel, a spring check or 50 detent, one of said wheel and detent elements mounted on the platen and the other on said head, a finger piece connected to said head, a line-spacing device including a pawl and lever, both mounted on one of said head and platen elements, a lever 55 mounted on the platen frame to operate said line-spacing devices, and an adjustable stop for said head.
6. In a typewriting machine, the combination with a revoluble platen and a platen frame, of a head mounted on the platen frame to turn concentrically with the platen, a brake to resist turning of said head, a line-space wheel, a spring check or detent, one of said wheel and detent elements mounted on 60 the platen and the other on said head, a crank to turn said head, and a stop to limit the throw of said head effected by said crank.
7. In a typewriting machine, the combination with a platen and a line-space wheel, of a line-space wheel actuator, means for reciprocating said actuator, means for rotating the platen together with said actuator, and stops for determining the strokes of 65 said rotating means.
8. In a typewriting machine, the combination with a platen and a platen frame, of a line-space wheel connected to the platen, a spring detent for said line-space wheel, a 70 head carrying said spring detent, and means for revolving said head through a predetermined number of line-space intervals.
9. In a typewriting machine, the combination with a platen and a platen frame, of a line-space wheel connected to the platen, a 75 spring detent for said line-space wheel, a head carrying said spring detent, and means for revolving said head through a predetermined number of line-space intervals; said 80 revolving means including a crank or lever and a stop for arresting said crank.
10. In a typewriting machine, the combination with a platen and a platen frame, of a line-space wheel connected to the platen, a 85 spring detent for said line-space wheel, a head carrying said spring detent, and means for revolving said head through a predetermined number of line-space intervals; said 90 revolving means including a crank or lever and relatively adjustable stops for limiting the strokes of said crank.
11. In a typewriting machine, the combination with a platen and a platen frame, of a line-space wheel connected to the platen, a 95 spring detent for said line-space wheel, a 100 head carrying said spring detent, means for revolving said head through a predetermined number of line-space intervals; said 105 revolving means including a crank or lever and relatively adjustable stops for limiting the strokes of said head and platen.
12. In a typewriting machine, the combination with a platen frame, of a platen mounted thereon, a line-space wheel, a line-space pawl mounted upon a head for rotative movement about the line-space wheel axis, a friction device opposing such movement of said head and pawl, means including a lever mounted upon said platen frame, for reciprocating said pawl to rotate the 110 platen step by step, a crank connected to said head to rotate the same, and a stop to limit the stroke of said crank. 85
13. In a typewriting machine, the combination with a platen frame, of a platen, a line-space wheel, a head mounted for rotation concentrically with the line-space wheel, stops for said head, a line-space pawl 90 mounted upon said head, a line-space detent also mounted upon said head, a manually operable part mounted upon the platen frame and effective to operate said pawl, and stops to limit the strokes of the manually 95 operable part.
14. In a typewriting machine, the combination with a platen frame, of a platen, a line-space wheel, a head mounted for rotation and provided with a crank or driver, a 100 line-space pawl, a lever upon said head whereon said pawl is mounted, a line-space detent also mounted upon said head, means upon the platen frame for actuating said lever at all rotative adjustments of said 105 head, and relatively adjustable stops for limiting the strokes of said head and platen.
15. In a typewriting machine, the combination with a platen frame, of a platen, a line-space wheel, a head mounted for rotation concentrically with said platen and line-space wheel, a crank for turning said head, stops to limit the strokes of said crank, a lever fulcrumed upon said head, a pawl carried by said lever for driving said line-space wheel, and a lever mounted upon the platen frame and effective to operate the first-mentioned lever at all adjustments of 115 said head.
16. In a typewriting machine, the combination with a platen frame, of a platen, a line-space wheel, a head mounted for rotation concentrically with said platen and line-space wheel and provided with a crank rigid thereto, a stop for limiting the stroke 120 of said crank, means between said platen frame and said head for frictionally opposing the rotation of said head, a lever fulcrumed upon said head, a line-space pawl 125 operated by said lever, and a lever mounted 130

upon the platen frame and effective to operate the first-mentioned lever at all adjustments of said head.

17. In a typewriting machine, the combination with a platen frame, of a platen, a line-space wheel, a head provided upon a crank and mounted for rotation concentrically with said platen and line-space wheel, stops for arresting said crank, a spring-pressed line-space detent upon said head and constantly engaging said line-space wheel, means between the platen frame and said head for frictionally opposing the rotation of the latter to such an extent that sufficient rotative force may be applied directly to the platen to overcome the opposition of said detent without rotating said head, a lever rotating with said head, a line-space pawl operable by said lever, and a lever mounted upon the platen frame and effective to operate the first-mentioned lever.

18. In a typewriting machine, the combination with a platen frame and a platen mounted thereon, of a line-space wheel, a head mounted for rotation, a line-space pawl and line-space detent both revolvable together with said head, a lever mounted upon the platen frame, a device also revolvable with said head and movable longitudinally of the platen by said lever for actuating said pawl to rotate said line-space wheel and platen independently of said head, and stops to limit the rotation of said head.

19. In a typewriting machine, the combination with a platen frame and a platen mounted thereon, of a line-space wheel, a head mounted for rotation and provided with a crank, stops to limit the rotation of said crank and head, a line-space pawl and line-space detent both revolvable together with said head, a lever mounted upon the platen frame, and a device also revolvable with said head and movable in axial direction by means of said lever for actuating said pawl to rotate said line-space wheel and platen independently of said head.

20. In a typewriting machine, the combination with a platen frame, of a platen, a line-space wheel, a head mounted for rotation and provided with a finger wheel, a brake for said head, a crank for said head, a stop for said crank, a collar mounted upon said head and movable axially thereof, a line-space pawl mounted for actuation by the axial movement of said collar, and a line-space lever mounted upon the platen frame and having a part to engage said collar for moving the same in axial direction.

21. In a typewriting machine, the combination with a platen frame, platen and line-space wheel, of a head mounted for rotation and provided with a crank, a stop for said crank, a brake for said head, a line-space detent mounted upon said head, a lever also

mounted upon said head, a line-space pawl actuatable by said lever, a collar splined upon said head and adapted by an axial movement to operate said lever, and a line-space lever mounted upon the platen frame; one of said collar and line-space lever elements having a groove, and the other having a cooperative projection engaging said groove.

22. In a typewriting machine, the combination with a platen frame, platen and line-space wheel, of a head mounted for rotation, relatively adjustable stops to limit the rotation of said head, a line-space detent upon said head, a lever also mounted upon said head, a sliding spring-pressed pawl mounted upon said lever and normally standing clear of said line-space wheel, and means for operating said lever at all adjustments of said head.

23. In a typewriting machine, the combination with a platen frame, platen and line-space wheel, of a head mounted for rotation concentrically with the platen and provided with a crank, means for frictionally opposing the rotation of said head, a stop for said crank, a spring-pressed line-space detent mounted upon said head, a lever also pivoted upon said head and provided with a sliding spring-pressed pawl, a collar splined upon said head and having a pin-and-slot connection with an arm of said lever, and a line-space lever fulcrumed at its rear end in rear of said head and projecting forwardly from the platen frame and having between its ends a pin-and-slot connection with said collar.

24. In a typewriting machine, the combination with a platen frame and platen, of a head journaled in the platen frame, a platen axle journaled within the head, a line-space detent mounted upon said head, a line-space pawl also carried by said head, means for actuating said pawl, a crank for said head, and a stop for said crank.

25. In a typewriting machine, the combination with a platen frame, platen and line-space wheel, of a head journaled in the platen frame, a brake for said head, a platen axle journaled within the head, an operating-crank upon said head outside of the platen frame, stops for said crank, a line-space detent and line-space pawl both carried by said head within said platen frame, and means, including a lever mounted upon the platen frame, for actuating said pawl at all adjustments of said head.

26. In a typewriting machine, the combination with a platen frame, platen and line-space wheel, of a tubular head journaled in the platen frame, a platen axle extending within said head, a crank upon said head outside of the platen frame, means for frictionally opposing the rotation of said head, stops for limiting the strokes of said head, a rack for one of said stops, a line-space de-

- tent and line-space pawl both carried by said head within said platen frame, a collar mounted within said platen frame for rotation with said head, a lever mounted upon 5 the platen frame, and having a part for engaging said collar to slide the same axially, and means for enabling said collar by its axial movement to actuate said line-space pawl.
- 10 27. In a typewriting machine, the combination with a line-space ratchet wheel and a platen, of a spring-pressed detent engaging said ratchet wheel and adapted to slip over the teeth thereof, a crank for effecting 15 rotative adjustment of said detent and ratchet wheel together, stops for said crank, and a rack for one of said stops.
28. In a typewriting machine, the combination with a line-space ratchet wheel and 20 a platen, of a spring-pressed detent engaging said ratchet wheel and adapted to yieldingly hold the same against rotation, means for effecting rotative adjustment of said detent and ratchet wheel together through 25 strokes each equal to many line-space intervals, and a line-space pawl also rotative with said ratchet wheel, and stops for limiting such strokes.
29. In a typewriting machine, the combination with a revolute platen, of mechanism 30 for imparting a step-by-step rotation thereto, and means for effecting strokes of the platen together with said mechanism through a stroke equal to many line space 35 intervals and back to initial position, and relatively adjustable stops for limiting such strokes.
30. In a typewriting machine, the combination with a platen and a platen frame, of 40 a head mounted for revolution in the platen frame, the platen having an axle extending through the head, a crank upon an end of the head that projects from the platen frame, a stop for said crank, a brake for 45 preventing accidental rotation of said head, a line-space ratchet wheel, and a detent being provided between said head and the platen, to enable the head to rotate the platen.
- 50 31. In a typewriting machine, the combination with a platen and a platen frame, of a head mounted for revolution in the platen frame, the platen having an axle extending through the head, a crank upon an end of 55 the head that projects from the platen frame, and a brake for preventing accidental rotation of said head, a line-space ratchet wheel, and a detent being provided between said head and the platen, to enable the head to rotate the platen, and said brake comprising a spring housed in the platen frame and compressed between an adjusting screw and a loose plug which bears against said head.
- 60 32. In a condensed billing mechanism, 65 the combination with a platen and a platen frame, of a crank provided with a rack, a stop adjustable along said crank upon said rack, and a volute series of stops to coöperate with said stop for arresting the platen.
33. In a condensed billing mechanism, the combination with a platen and a platen frame, of a crank provided with a rack, a stop adjustable along said crank upon said rack, and a volute series of stops to coöperate with said stop for arresting the platen, 70 said rack consisting of notches formed on opposite sides of the crank for engagement by a forked portion of the first-mentioned stop.
34. In a condensed billing mechanism, the combination with a platen and a platen frame, of a crank provided with a rack, a stop adjustable along said crank upon said rack, and a volute series of stops to coöperate with said stop for arresting the platen, 75 said rack consisting of notches formed on opposite sides of the crank for engagement by a forked portion of the first-mentioned stop, 80 said series of stops being formed upon a plate which is secured to the platen frame.
35. In a condensed billing mechanism, the combination with a platen and a platen frame, of a crank provided with a rack, a stop adjustable along said crank upon said rack, a volute series of stops to coöperate 85 with said stop for arresting the platen, said rack consisting of notches formed on opposite sides of the crank for engagement by a forked portion of the first-mentioned stop, 90 said series of stops being formed upon a plate which is secured to the platen frame, and a stop to limit the return stroke of said crank and platen to initial position.
36. In a typewriting machine, the combination with a revolute platen and a platen frame, of a head mounted in the platen frame and having a crank or driver, means opposing the revolution of said head, a line-space wheel and detent connecting the head to the platen, a part upon said head having a helical cam, a thrust pin engaged by said cam, a sliding collar upon said head and having a shoulder to be engaged by said thrust pin, and platen-rotating means actuated by said sliding collar, whereby upon actuating said crank or driver the platen may be turned backwardly to receive a new sheet and simultaneously advanced to produce a blank between entries upon the record sheet which remains in the machine.
37. In a typewriting machine, the combination with a revolute platen and a platen frame, of a head mounted in the platen frame and having a crank or driver, means opposing the revolution of said head, a line-space wheel and detent connecting the head to the platen, a part upon said head having a helical cam, a thrust pin engaged by said cam, a sliding collar upon said head and having a shoulder to be engaged by said 105
- 110
- 115
- 120
- 125
- 130

thrust pin, and platen-rotating means actuated by said sliding collar, whereby upon actuating said crank or driver the platen may be turned backwardly to receive a new sheet and simultaneously advanced to produce a blank between entries upon the record sheet which remains in the machine, said cam part disconnectible to permit operation of the crank or driver without effecting automatic advance of the platen through its line-spacing mechanism.

38. In a typewriting machine, the combination with a platen and a line-space wheel, of a detent for said line-space wheel, 5 a handle, means for enabling said handle to move said detent together with said line-

space wheel forwardly and backwardly, and stops to limit the strokes of the detent and line-space wheel.

39. In a typewriting machine, the combination with a platen and a line-space wheel, of a detent pressed by a spring against the teeth of said wheel, a member having a finger-piece and connected to said detent to move it and the wheel and platen 20 to and fro, and a stop to determine the initial position of said chamber.

BURNHAM C. STICKNEY.

Witnesses:

K. FRANKFORT,
JOHN O. SEIFFERT.

Correction in Letters Patent No. 1,007,746.

It is hereby certified that in Letters Patent No. 1,007,746, granted November 7, 1911, upon the application of Burnham C. Stickney, of Elizabeth, New Jersey, for an improvement in "Type-Writing Machines," an error appears in the printed specification requiring correction as follows: Page 7, line 27, for the word "chamber" read *member*; and that the said Letters Patent should be read with this correction therein that the same may conform to the record of the case in the Patent Office.

Signed and sealed this 28th day of November, A. D., 1911.

[SEAL.]

E. B. MOORE,
Commissioner of Patents.
